(57) **CLAIM**

The ornamental design for a transparent keypad and keypad housing, substantially as shown.

DESCRIPTION

FIG. 1 is a front perspective view of a first embodiment of a transparent keypad and keypad housing showing our new design;

FIG. 2 is a front view of the embodiment as shown in FIG. 1;

FIG. 3 is a back view of the embodiment shown in FIG. 1; FIG. 4 is a right side view of the embodiment shown in FIG. 1;

FIG. 5 is a left side view of the embodiment shown in FIG. 1;

FIG. 6 is a top view of the embodiment shown in FIG. 1; FIG. 7 is a bottom view of the embodiment shown in FIG. 1;

FIG. 8 is a front perspective view of a second embodiment of FIG. 1.

FIG. 9 is a front view of the embodiment as shown in FIG. 8;

FIG. 10 is a back view of the embodiment shown in FIG. 8; FIG. 11 is a right side view of the embodiment shown in FIG. 8;

FIG. 12 is a left side view of the embodiment shown in FIG. 8;

FIG. 13 is a top view of the embodiment shown in FIG. 8; and,

FIG. 14 is a bottom view of the embodiment shown in FIG. 8.

The broken line showing of the environment is for illustrative purpose only and forms no part of the claimed design.
